(57) **CLAIM**

We claim the ornamental design for a mirror, as shown and described.

DESCRIPTION

FIG. 1 is a perspective view of a mirror according to an embodiment of the invention.

FIG. 2 is a top plan view of a mirror according to an embodiment of the invention.

FIG. 3 is a front elevational view of a mirror according to an embodiment of the invention; and,

FIG. 4 is a side view of a mirror according to an embodiment of the invention, the opposite side being a mirror-image thereof.
